J. H. Gibbs ATTORNEY.

UNITED STATES PATENT OFFICE.

BENJAMIN HUGHES, OF MONTREAL, AND HERBERT NOEL YOUNG, OF ROCKFIELD, QUEBEC, CANADA, ASSIGNORS TO G. ALFRED MORRIS, OF MONTREAL, CANADA.

EXTENSION-LADDER.

No. 856,875.

Specification of Letters Patent.

Patented June 11, 1907.

Application filed April 9, 1906. Serial No. 310,793.

To all whom it may concern.

Be it known that we, BENJAMIN HUGHES and HERBERT NOEL YOUNG, subjects of the King of England, and residing at Montreal and Rockfield, respectively, in the Province of Quebec, in the Dominion of Canada, have invented certain new and useful Improvements in Extension-Ladders, of which the following is a specification.

This invention relates to extension ladders, the object of the invention being to produce a ladder of that class which may be easily and quickly raised and lowered when desired, and which will possess means for securely locking the slidable section in any desired position, there being also provided attachments designed to reinforce the structure and to lessen friction in the operation thereof, all as hereinafter more fully described and specifically pointed out in the claims.

In the accompanying drawings similar letters of reference and characters of reference denote corresponding parts in all the views.

Figure 1 is a front elevational view of the ladder partly extended; Fig. 2 is a side elevational view, with part of one of the side rails broken away; Fig. 3 is a rear elevation of one of the hooks and its integral sleeve; Fig. 4 is a side elevational view of the same part; Fig. 5 is a rear elevational view of the lever sleeve and lever; Fig. 6 is a side elevational view of the same part; Fig. 7 is a top plan view of one of the castings which are attached to the upper ends of the side rails of the base section of the ladder; Fig. 8 is a side elevational view of the same part; Fig. 9 is a side elevational view of one of the castings attached to the lower end of the side rails of the base section of the ladder and Fig. 10 is a top plan view of the same member.

Referring to the parts —A— is the base section of the ladder, —B— is the slidable section of the same, —C— is a sheave which is attached by any suitable means to one of the rungs —d—, preferably the top rung, of the base section, and —E— is the manipulating rope or cable by means of which the slidable section is raised.

Upon the rung —e— of the base section are placed a plurality of sleeves —1— respectively, and to the sleeves —1— are cast the hooks —3— there being also counter weights —4— cast integral therewith, said counterweights being adapted to hang as

shown in Fig. 2 so as to project the hooks 55 into position to readily receive the rungs of the slidable section of the ladder when it is lowered, but there is a lever —5— cast integral with the sleeve —2— and said lever —5— is long enough to extend into the path 60 of travel of said rungs so as to be impinged thereby in ascending and descending.

Each of the sleeves —1— and —2— is provided with shoulders —6— as shown best in Figs. 3 and 5, and said shoulders are so positioned when the sleeves are in position on said rung that the lever —5— may be thrown upwardly without disturbance of the hooks, but in the event of the lever —5— remaining on the lower side of any given rung of the 70 slidable section while the hook is also on the lower side of the same rung, which shall be considered the nearest rung, then said shoulders will become interlocked in such manner as to retract the hooks —3— when the said 75 rung will impinge the lever —5— and it will be evident that the extension, or upper section, may now be lowered to the ground.

If it is desired to lock the slidable section at any point all that is necessary is to raise the 80 slidable section to such position that the lever —5— and the adjacent hooks —3— are on opposite sides—top and bottom—of the adjacent rung of the ladder as shown in Fig. 2 so as to carry the engaging shoulders —6— 85 out of operative position, whereupon the ladder will be locked in position as soon as the upper section is lowered to permit the rung above said hooks to rest upon the hooks.

By making the hooks and lever integral 90 with said sleeves it is evident that they may be supported by one of the rungs of the ladder and no extra means of attachment are required.

At the lower end of the slidable section 95 —B— and at the upper end of the fixed base section —A— are provided castings —7— and —8— respectively, said castings being substantially alike in general form. Each of these castings carries a pair of friction reducing rollers —9— which are so disposed as to be at opposite sides of the slidable ladder section, the said slidable section floating between said rollers in use, and integral with each of these castings —7— 8— are cheek-pieces —10— which are perforated for the passage therethrough of one of the rungs, as —d— to hold said castings in position,

there being also perforated flanges —11— formed integral with said castings so that bolts —12— may be passed therethrough for the purpose of assisting to hold said castings in position to carry the friction reducing rollers before referred to.

When the castings are used it is evident that no boring of the side rails is required to secure them on the said rails as the rung passing through the perforation in the cheek plates aided by the bolts passing through the flanges —11— will be sufficient for that purpose.

At the upper ends of the extension member of the ladder are roller carrying castings —13— in which are rotatably mounted the rollers —14— which may rest against the wall of the building while the extension is being raised, and foot castings —15— are secured to the lower ends of the base section with spiked extensions cast thereon which are adapted to engage with the surface on which the ladder rests, though it is evident that instead of the spikes there may be foot pieces of rubber or other yielding material substituted if desired.

Having described our invention, what we claim as new is:

1. In an extension ladder comprising a base section and a slidable section, the combination with a shouldered sleeve carrying a counterbalanced hook, a shouldered sleeve carrying a lever and means for elevating said slidable section.
2. In an extension ladder comprising a base section and a slidable section, the combination with a shouldered sleeve carrying a counterbalanced hook, an intermediate shouldered sleeve carrying an integral lever, means for elevating said slidable section, guide rollers at opposite sides of said slidable section, a casting supporting said rollers and

a cheek piece, provided with a perforation, formed integral with said casting.

3. In an extension ladder comprising a base section and a slidable section, the combination with a shouldered sleeve carrying a lever, of a pair of shouldered sleeves, each of which carries a hook which is adapted to be retracted by said lever.

4. In an extension ladder comprising a base section and a slidable section, the combination of a rockable shouldered sleeve carrying an integral hook at each of the ends of and rotatable on a rung of said ladder, and an intermediate shouldered sleeve on said rung and carrying an integral lever adapted to engage said hook carrying sleeves at predetermined times.

5. In an extension ladder, a base section with rungs, a slidable section with rungs, interlockable sleeves on opposite end portions of one rung of the base section, a hook integral with said sleeves and a throw off lever integral with an intermediate sleeve, there being shoulders on said intermediate sleeve adapted to engage said interlockable sleeves at predetermined times.

6. In an extension ladder, the combination comprising a base section, a slidable section, rockable and shouldered sleeves carried by one rung of said base section, hooks integral with some of said sleeves, a throw off lever integral with an adjacent sleeve carried on the same rung and shoulders on said lever sleeve adapted to engage the hook carrying sleeve.

In witness whereof we have hereunto set our hands in the presence of two witnesses.

BENJAMIN HUGHES.
HERBERT NOEL YOUNG.
